UNITED STATES PATENT OFFICE.

RUSSELL WILLIAM MUMFORD, OF NEW YORK, N. Y., ASSIGNOR TO REFINING PRODUCTS CORPORATION, OF WILMINGTON, DELAWARE, A CORPORATION OF DELAWARE.

PROCESS OF MAKING SUGAR.

1,314,203.

Specification of Letters Patent. Patented Aug. 26, 1919.

No Drawing.

Application filed June 29, 1917. Serial No. 177,820.

To all whom it may concern:

Be it known that I, RUSSELL WILLIAM MUMFORD, a citizen of the United States, residing at New York, in the county of New

5 York and State of New York, have invented certain new and useful Improvements in Processes of Making Sugar, of which the following is a specification.

This invention relates to processes of 10 making sugar; and it comprises a method of treating sugar liquors, syrups, molasses and all other saccharine solutions wherein a sugar juice or solution, with or without a preliminary purification, is treated with 15 a particular type of vegetable carbon having the power of taking gummy and coloring matter out of solution and also having the power of taking up or flocculating fine suspended matter, the solution being there- 20 after evaporated to produce crystallization, such vegetable carbon being an open-textured and porous rather coarse material produced by slow carbonization of various vegetable matters in the presence of sufficient oxidiz- 25 ing gases to keep the pores open and free of carbon deposits; all as more fully hereinafter set forth and as claimed.

Stated in broad terms, the process of manufacturing sugar from vegetable materials 30 consists in evaporating a solution, such as a vegetable juice, containing the same, until it is so concentrated that sugar crystallizes out and the main problem before the manufacturer, aside from evaporation, is 35 that of clarifying, purifying and decolorizing his solutions. Vegetable juices and saps, such as those obtained from sugar cane, sorghum, beets, etc., of course contain very many things other than sugar, albu- 40 minoids, amids, salts, coloring matter, gums, etc. Not all these matters which must be removed as far as possible for efficient and economical working are in solution; much of the impurity is in suspension and in the 45 colloidal forms of solutions that approach suspensions. In a general way it may be said that these colloidal and suspended matters are very detrimental since they impede the crystallization.

50 In the manufacture of sugar from sugar cane, and also from sorghum, the juice is expressed from the cane by means of cane crushers and rollers in ways unnecessary to detail here. To this juice, which is a tur- 55 bid liquid containing suspended fragments of cane, etc., is added lime, to effect the

neutralization of the natural acidity of this juice, and the mixture is then heated to a temperature of about 98° C. (200° F.), up to the so-called "cracking" point. 60

When this point has been reached, a part of the impurities in the juice rise to the surface as a scum, and the remaining impurities, in greater part, settle to the bottom of the vessel in which the reaction is carried 65 on. Sometimes a little acid phosphate is employed, together with the lime, in order to produce a greater separation. In some raw sugar factories the scum thus formed is brushed off and the juice is clarified further 70 by additional boiling and brushing. In many plants, however, the liquid juice is, after heating, allowed to settle in special defecation tanks and the clarified juice is decanted from the impurities; these are 75 known as scum, mud, or slops. These scums and deposits are then sent through a mud-press, which retains them as press cakes, and the juice flowing therefrom is added to the clarified juice previously decanted. 80 Separation of the mechanical impurities in the brief time permitted is not complete; it is rare that the juice goes to the evaporators in an absolutely bright and clear condition. This preliminary purification treat- 85 ment or defecation, does not remove any large amount of the impurities or the coloring matter. Gummy soluble impurities are not affected to any extent. After evaporation the dissolved and the mechanical im- 90 purities of course remain in the thick syrupy product from which it is now difficult to separate them.

The next step in the process of making raw cane sugar is the concentration of the 95 clarified juice by evaporation under a vacuum into a fairly thick syrup. This syrup is finally evaporated to crystallization; and the thick magma of sugar crystals and molasses is then separated in centrifugals, etc. 100

In the manufacture of raw sugar from the sugar beet, the sugar beets, after having been thoroughly cleaned and washed, are sliced into thin, narrow strips called cossettes; these are placed in diffusion batteries and 105 the sugar in them is extracted with hot water. The sugar solution thus obtained is known as diffusion juice. This diffusion juice, after being subjected to one or more processes of purification, is concentrated to 110 the so-called "thick liquor" which is then boiled to crystallization. The magma of

sugar crystals and molasses is then separated in centrifugals, etc.

Obviously, in the crystallization operation when the syrup is boiled to grain, the 5 yield of crystallized sugar and its quality depend upon the purity of the juice which is submitted to graining. Ordinarily the purity is not sufficient to give a product of a quality suitable for direct consumption 10 either in the case of cane or beets. Sometimes raw cane sugar is submitted to drastic washing and other treatments to give a "plantation white sugar". In beet sugar factories, the raw sugar is sometimes directly converted into white sugar for the 15 market by operations involving chemical bleaching. Ordinarily, however, raw cane sugar and raw beet sugar are redissolved in water and submitted to refining.

20 In refining sugar, whether raw cane sugars or raw beet sugars be used, the dissolved or "melted" raw sugar is usually defecated and clarified by the use of lime and soluble monocalcium phosphate, or phosphoric acid; 25 the resultant precipitate, which holds imprisoned in it most of the mechanically suspended impurities, is removed by passing the liquid through either filter bags or filter presses. Sometimes kieselguhr is used as a 30 filtering agent in these refining operations. The resulting brown sugar solution is then led through boneblack cylinders in order to remove color and impurities, and is then further concentrated by evaporation. It is sent 35 to vacuum pans where it is boiled to crystallization.

I have found that if I submit the juices or semi-syrups produced to the action of a 40 particular material, which I may here call a "decolorant", I can not only remove the dissolved impurities, and particularly the color-giving impurities, but also the suspended impurities and the quasi-dissolved or suspended colloids in one operation. Many 45 kinds of carbon, as in the case of boneblack, are known to remove dissolved matter from sugar juice and enhance its purity. Some highly porous non-carbonaceous materials, like kieselguhr (diatomaceous earth), have another and different action on sugar juices, 50 in that they remove the materials which are strictly in suspension, giving clear or what are known as "bright" liquors, while they have practically no effect on the dissolved or quasi-dissolved matter. I have found 55 that with my decolorant I can unite both these actions, removing at once the dissolved impurities and the suspended or quasi-suspended colloid materials from sugar 60 solutions; producing in one operation a syrup sufficiently clarified, purified and decolorized to allow its being sent to the grain- 65 ing pan to produce directly sugars of a refined type. In other words, I simultaneously decolorize and produce bright liquor,

obtaining in one operation two distinct results, and also effecting a marked economy, or what is the same thing, increasing the capacity of the factory. The present methods of producing sugar require many hours 70 to produce the results that in the present method are produced in an hour.

This decolorant I produce by a special method of charring vegetable matters, such as peat or sawdust, as more fully set forth 75 in my copending application, Serial No. 167,971. Briefly stated, the method as disclosed in the said application in an advantageous embodiment, is to treat peat or sawdust or other vegetable matter with a highly 80 colloid material, like starch, in the event that such vegetable material does not already contain a sufficient amount of colloid materials. The vegetable material in a granulated form is then mixed with grains of a 85 material, such as dolomite, adapted to act as a spacing agent and also to evolve carbon dioxid or other purifying gas continuously throughout a wide temperature range. The mixture is then slowly heated 90 in a vented retort. Under the action of the heat, the moisture is first expelled, taking with it various volatile matters and puffing up the vegetable material and rendering it 95 porous. Then the material chars slightly, giving off various vapors and gases. Because of the presence of the mineral spacing 100 agent, these vapors and gases are afforded an opportunity to escape without in their turn undergoing decomposition in the presence of the grained vegetable matter. As the charring goes on the dolomite begins to 105 evolve carbon dioxid at a temperature somewhere around 250° C. This carbon dioxid is taken up in the pores of the charring 110 mass and as the temperature goes up, it exercises a beneficial action on these pores, probably by opening them up. The temperature is then carried to a high point and the material is dumped into water and 115 washed. The ultimate material is a granular carbon having open pores representing, more or less closely, the cellular structure 120 of the original material before carbonization. It is more open-textured than charcoal 115 in which, in the usual methods of making charcoal, the pores are more or less closed and sealed by the deposition of carbon in them. When wood is first charred in making charcoal, the vapors and gases accumulate in the pores where they are in turn carbonized, depositing what may be termed secondary carbon in the pores and tending to close such pores. This is desirable in making charcoal where a hard, dense product is 125 wanted. In the present material, the effort is to have open pores substantially free of secondary carbon and capable of collecting suspended solids.

As I have found, a carbon prepared as 130

described when added to sugar solutions and syrups takes the coloring matter out of solution and also attracts or flocculates suspended and quasi-suspended impurities.

5 In a practical embodiment of the present process of making cane sugar, cane juice may first be obtained and defecated in the usual ways as hereinbefore set forth, and then concentrated by evaporation to produce 10 a syrup. I may, but less advantageously, dispense with this preliminary evaporation or concentration and treat the juice as it comes from the presses, but ordinarily I concentrate the juice to syrup or semi-syrup 15 prior to applying the present process.

The syrup does not need to be specially acidified when my decolorant is added and no heating to any particular degree or boiling is essential, but the solution must not 20 be alkaline. My decolorant acts effectively on cold neutral and non-acidified solutions, but if heating to say 85° C. or 90° C. or acidifying is deemed advantageous in the general manufacturing process of the raw 25 sugar or is deemed necessary to expedite subsequent filtration, it may be done.

After thoroughly mixing my decolorant with the syrup, the agitation may be continued for some time, say about from 10 to 30 15 minutes, either by stirring or by the use of an air blast. The mixed solution should then be sent through a filter press.

The filtered juice will be then found to be 35 very light in color; all, or nearly all, of its color having been removed. It is not merely bleached, because my decolorant actually retains the coloring matters. The decolorant also takes up the gummy and dissolved impurities which retard crystallization in the 40 ordinary methods. And it takes up in some manner all the suspended materials so that the filtered material is absolutely bright.

The filtered, bright, clear juice may be sent to the graining apparatus and evaporated down to crystallization, giving a 45 white sugar fit for direct consumption. In the manufacture of so-called "plantation white sugars" my decolorant is best applied to a syrupy liquid, as above described.

50 It is possible however, although less advantageous, to use the decolorant at other stages; that is, prior to a concentration to a syrupy product. It may, for example, be applied to a juice which has undergone the usual defecation and clarifying treatments; to the juice as it comes from the defecators and before it goes to the evaporators. It is even possible to use my decolorant with the raw cane juice at the time, or prior to the 55 time, of liming the juice, but although there is thus obtained at once a clarified juice much brighter, purer and much lighter in color than could otherwise be obtained, I do not deem it so advantageous to add the decolorant at this stage for two reasons. In

the first place, not all of the purifying and decolorizing power of my decolorant is utilized, owing to the envelopment of the particles by clogging impurities; in the second place, recovery of the decolorant for further 70 use is commercially much more difficult on account of the many impurities with which it becomes mingled.

To recover my material, the cakes of the decolorant formed in the filter presses are 75 first thoroughly sweetened off, by hot water, in the presses. The cake is then removed from the presses and the material boiled with a weak solution of caustic soda of, say, 2 to 10 per cent. in strength. This treatment 80 extracts principally the coloring matters which the decolorant has taken up from the sugar solutions. Finally, the decolorant is treated with dilute hydrochloric acid, in strength and amount sufficient to remove all 85 the caustic soda remaining in the decolorant. Another thorough washing with water follows, washing being continued until all of the salt formed and any free acid which may have remained have been removed. The material 90 can then be dried and it is ready for use again. Or the drying may be omitted and the wet material used directly.

In the treatment of beet juice, the juice may be obtained and purified or defecated 95 as hereinbefore described. It is best to add the decolorant to the somewhat concentrated or evaporated and syrupy material obtained after the usual defecating and clarifying steps hereinbefore described. I may use, as 100 before, the raw juices, or I may use the clarified juice prior to any concentration, but I find it best to work with the more or less concentrated or syrupy material. To the juice or the syrupy material, I add my decolorant and agitate thoroughly for some 105 time, say about from 10 to 15 minutes. Mechanical agitation of any suitable type may be used; or agitation may be by air blown in. My decolorant acts on cold non-acidified 110 or neutral solutions, but the juices or syrups may be acidified and heated to 85° C. or 90° C. if deemed advisable for any reason. The mixture of juice and decolorant is then sent through filter presses, and thence goes to the 115 vacuum pan in the manner stated in regard to the manner of making cane sugar.

The sugar juices coming from the filter press will be found to be absolutely water white in color. No bleaching by sulfur in 120 any form, hyposulfites, ozone, etc., is required. And the sugar after having been crystallized will have no tendency toward "going off" in color. Recovery of my decolorant and its revivification by washing 125 are of course exactly as before described.

My decolorant may be used in refining raw sugars, being dissolved or melted in the "blow-ups" as hereinbefore described. However, in using the present method em- 130

ployment of phosphoric acid or phosphates or kieselghur may be entirely obviated. With the solution is mixed my decolorant; ten to fifteen minutes under constant stirring or agitation being allowed for the action of the decolorant. The sugar solution during this time is kept under the temperature conditions usual in blow-up work, but no acidifying of the solution is necessary

10 nor is the attainment of any particular degree of heat. If however acidification is desired for other reasons, it may be resorted to, but I desire it to be understood that it is not necessary to acidify the sugar solution 15 in order to obtain the decolorizing action of my decolorant. The use of bleaching acids is neither essential nor desirable, nor is it essential to heat the solution to any particular high temperature or to boil it. Acidification or heat is not necessary although 20 both or either may be employed if desired. The solution containing the decolorant is finally sent through a filter press to recover the decolorant. The decolorant is then subsequently revivified by washing, etc., as before described.

If it is desired to use the customary treatment with phosphoric acid or monocalcium phosphate and milk of lime followed by 30 kieselguhr, this may be done. In this event, I advantageously add my decolorant to the sugar solution after it comes from the filter bags or filter presses, and just before it is sent on to the boneblack cylinders. The 35 added decolorant should be allowed 10 to 15 minutes for its action during which time it is to be thoroughly mixed with the sugar solution under constant stirring or agitation. If desired a hose with compressed air may 40 be used to keep the solution uniformly agitated for the purpose of mixing the decolorant therewith. I desire it to be distinctly understood that no acidifying of the solution is necessary in order to obtain a decolorizing 45 action with the present decolorant or in order to set up a bleaching action by such acid, and no particular degree of heat or boiling is required in order to obtain the desired actions with my decolorant. Acid 50 may however of course be added if the refiner prefers to do so, and the solution may, if desired, be heated up to about 85° or 90° C.

My process may be applied in one or more 55 stages. As I have just described it, there is but a single treatment with my decolorant, but my decolorant may be very advantageously applied in small quantities at a further station in the process of making sugar, 60 and its use at this second station is advantageous, and particularly with the "thick liquors" just before the same are sent to the pan for graining. The use of the decolorant in a plurality of portions at different 65 stages of manufacture is equally useful

in making beet sugar, making cane sugar and in refining raw sugar. For example, the sugar juices after the clarification may be treated with a portion of my decolorant and separated, be then concentrated to a 70 syrupy condition and more added, and so on. There may be as many of these additions at as many different stages between the juice or solution and the sugar as may be desired. A small percentage of my decolorant on the solids in the solution is usually sufficient, and five minutes ordinarily suffice for the action of my decolorant in a second application. On subsequent removal of the decolorant by filter press any slight cloudiness of the thick liquors will have entirely disappeared and water white sparkling thick liquors are the result of the treatment with my decolorant. I desire it to be particularly understood that no acidifying of the solutions is necessary and no special high temperature is required, although acid may be added if the refiner prefers to do so.

While I have hereinbefore described the use of my material particularly with juices and materials containing cane or beet sugar, yet the present method may also be advantageously used with solutions containing other sugars. It may, for example, be used in whitening and purifying glucose solutions. In so doing, the so-called "steeping solutions" may be treated with my decolorant and the solution then evaporated to a more or less syrupy condition and treated a second time if desired with a small percentage of my decolorant in the manner hereinbefore described. The whitened and brightened syrup may then be sent to the evaporators for final concentration.

The present method obviates the necessity 105 of using sulfur in the sugar industry in any form. It also renders bleaching agents unnecessary, for the present decolorant actually removes the color, taking it out of the solution instead of merely bleaching it or 110 masking it, as is done by sulfurous acid, the sulfites, hyposulfites, ozone, etc., frequently recommended for the purpose. When my decolorant is used there can be no subsequent "going off" in color as is often found in the 115 final products when bleaching is resorted to.

I regard the present process as applicable to any juice or solution containing sugar, whether the same be a raw juice, a clarified juice, a syrup, a semi-syrup, a molasses or 120 any other form of sugar solution; and the sugar solution to be purified need not necessarily be a solution of sucrose (cane sugar)—it may be a solution of other sugar, glucose, maltose, lactose, etc. In its best embodiment, however, the present process comprises heating such a sugar solution to obtain defecation and separation of the coarse fragments or mechanically suspended impurities as far as possible, and thereafter adding 125 130

my decolorant in one or more stages; the reason for the preliminary separation of impurities by defecation or clarification being of course to prevent clogging of my material. With most of these liquids a heating prior to or during defecation is advantageous in promoting separation of impurities.

What I claim is:—

1. The process of purifying sugar solutions which comprises defecating the same to separate coarse fragments of mechanically suspended impurities as far as possible, adding to and agitating with the defecated liquid a porous open-textured carbon produced by the slow carbonization of vegetable matter under circumstances maintaining an open texture, such carbon having pores substantially unobstructed by secondary carbon and adapted to take up and retain fine insoluble suspended matter, separating the carbon and evaporating the sugar liquids to crystallization.

2. The process of purifying sugar solutions which comprises heating and defecating the turbid liquid to separate coarse fragments of mechanically suspended impurities as far as possible, adding to the liquid in a neutral condition a porous open-textured carbon produced by the slow carbonization of vegetable matter under circumstances maintaining an open porous structure, such carbon having pores substantially unobstructed by secondary carbon and adapted to take up and retain fine insoluble suspended matter, separating the carbon and evaporating the liquid to crystallization.

3. In the purification of sugar solutions to remove dissolved and suspended impurities, the process which comprises vigorously agitating such solutions with a relatively coarse grained vegetable carbon having open pores corresponding substantially to the original texture of the material from which such carbon was made, such carbon having pores substantially unobstructed by secondary carbon and adapted to take up and retain fine insoluble suspended matter.

4. In the purification of sugar solutions to remove dissolved and suspended impurities, the process which comprises defecating such a solution to remove dissolved and suspended impurities as far as possible, vigorously agitating the defecated solution with a relatively coarse grained vegetable carbon, having open pores corresponding substantially to the original texture of the materials from which such carbon was made, such carbon having pores substantially unobstructed by secondary carbon and adapted to take up and retain fine insoluble suspended matter.

5. In the purification of sugar solutions the process which comprises vigorously agitating such solutions in a thick and syrupy condition with a relatively coarse grained vegetable carbon having open pores corre-

sponding substantially to the original texture of the material from which such carbon was made, such carbon having pores substantially unobstructed by secondary carbon and adapted to take up and retain fine insoluble suspended matter.

6. In the purification of sugar solutions the process which comprises defecating such a solution, removing separated coarse fragments of impurities as far as practicable, mixing the liquid with a porous open-textured vegetable carbon, having open pores corresponding substantially to the original texture of the material from which such carbon was made, such carbon having pores substantially unobstructed by secondary carbon and adapted to take up and retain fine insoluble suspended matter, the mixing being continued for a time under agitation, separating the carbon by filter pressing and evaporating the purified liquid to crystallization.

7. In the purification of sugar solutions to remove dissolved and suspended impurities, the process which comprises vigorously agitating such solutions in a neutral condition with a relatively coarse grained vegetable carbon having open pores corresponding substantially to the original texture of the material from which such carbon was made, such carbon having pores substantially unobstructed by secondary carbon and adapted to take up and retain fine insoluble suspended matter.

8. In the purification of sugar solutions to remove dissolved and suspended impurities, the process which comprises evaporating such solutions to a thick or syrupy condition, vigorously agitating in a neutral condition with a relatively coarse grained vegetable carbon having open pores corresponding substantially to the original texture of the material from which such carbon was made, such carbon having pores substantially unobstructed by secondary carbon and adapted to take up and retain fine insoluble suspended matter.

9. In the purification of sugar solutions to remove dissolved and suspended impurities, the process which comprises defecating such a solution to remove coarse fragments of separated impurities as far as practicable, mixing the liquid in a neutral condition with a porous open-textured vegetable carbon having open pores corresponding substantially to the original texture of the material from which such carbon was made, such carbon having pores substantially unobstructed by secondary carbon and adapted to take up and retain fine insoluble suspended matter, the mixing being continued for a time under agitation, separating the carbon by filter pressing and evaporating the purified liquid to crystallization.

10. In the purification of sugar solutions

6
to remove dissolved and suspended impurities, the process which comprises defecating such a solution to remove coarse fragments of separated impurities as far as practicable, mixing the liquid in a neutral condition with a porous open-textured vegetable carbon having open pores corresponding substantially to the original texture of the material from which such carbon was made, 5 such carbon having pores substantially unobstructed by secondary carbon and adapted to take up and retain fine insoluble sus-

pended matter, the mixing being continued for a time under agitation, separating the carbon by filter pressing, evaporating the 15 purified liquid to a thicker syrup, adding a small amount of the open-textured carbon to such thicker syrup, agitating, again filter pressing, and finally evaporating the resultant clarified and decolorized liquid to crystallization. 20

In testimony whereof, I affix my signature hereto.

RUSSELL WILLIAM MUMFORD.
